UNITED STATES PATENT OFFICE.

FRANKLIN WOODS, OF PHILADELPHIA, PENNSYLVANIA, ASSIGNOR TO
ALVONI R. ALLEN, OF WYCKOFF, NEW JERSEY.

DESIGN FOR A CORNER-STRIP.

SPECIFICATION forming part of Design No. 27,016, dated May 4, 1897.

Application filed March 30, 1897. Serial No. 629,987. Term of patent 7 years.

To all whom it may concern:

Be it known that I, FRANKLIN Woods, a citizen of the United States, residing in Philadelphia, Pennsylvania, have invented a certain new and original Design for a Corner-Strip, of which the following is a specification.

My design for a corner-strip for plastered walls consists, essentially, of a perforated body portion having wings projecting alternately in opposite directions.

The figure in the drawing represents the strip in perspective.

A is the body portion of the strip, having a series of large and small perforations $a a'$. Projecting on a line with the large perforations are wings $b b'$. The wings are alter-

nately bent, one set, b , being bent in one direction and the other set, b' , being bent in the opposite direction. The wings are spaced, as clearly shown in the drawing.

20

I claim—

The design for a corner-strip for plastered walls as herein described and as shown in the accompanying drawing.

In testimony whereof I have signed my name to this specification in the presence of 25 two subscribing witnesses.

FRANKLIN WOODS.
